UNITED STATES PATENT OFFICE.

FRANK STEWART, OF CHICAGO, ILLINOIS, ASSIGNOR TO THE STOCKHAM MANUFACTURING COMPANY, OF SAME PLACE.

DESIGN FOR A TABLE-TOP.

SPECIFICATION forming part of Design No. 29,846, dated December 20, 1898.

Application filed October 17, 1898. Serial No. 693,829. Term of patent 7 years.

To all whom it may concern:

Be it known that I, FRANK STEWART, a citizen of the United States, residing at Chicago, in the county of Cook and State of Illinois, have invented and produced a new and original Design for Table-Tops, of which the following is a specification, reference being had to the accompanying drawings, in which—

Figure 1 illustrates my new design of a table-top by a plan view, and Fig. 2 is an edge view of the top.

As shown in the drawings, the leading or material feature of my design consists of the top A, having the ornamental open-work frame B of the general rectangular shape illustrated, with the center C representing onyx. The corner-pieces o o of the frame

describe right angles and contain medallions m, and the connections n from one corner-piece to the other are curved, as shown, and ²⁰ meet at the center between each pair of the corner-pieces in a medallion m'. The open-work in the frame B is in the form of fantastic leaves l, the whole being in the general style of Louis XVI ornamentation. ²⁵

Having described my invention, what I claim as new, and desire to secure by Letters Patent, is—

The design for a table-top, as herein shown and described.

FRANK STEWART.

In presence of—

R. P. SPANCER,
D. W. LEE.
